United States Patent Office

Des. 191,797
Patented Nov. 21, 1961

191,797

DOOR LATCH

Roger Mark Singer, Rego Park, N.Y., assignor to Proctor & Schwartz, Inc., Philadelphia, Pa., a corporation of Pennsylvania

Filed Dec. 20, 1960, Ser. No. 63,284

Term of patent 14 years

(Cl. D50—5)

FIG.1

FIG. 2

FIG. 3

FIG.4.

FIG.5.

FIG.6.

FIG.7.

FIG.8.

FIGURE 1 is a top plan view of a door latch, showing my new design;

FIGURE 2 is a front elevational view;

FIGURE 3 is a bottom plan view;

FIGURE 4 is an elevational view of one end;

FIGURE 5 is an elevational view of the end opposite that of FIG. 4;

FIGURE 6 is a front perspective view;

FIGURE 7 is a perspective view of the latch in door-releasing position; and

FIGURE 8 is a fragmentary perspective view of the base portion of the latch.

I claim:

The ornamental design for a door latch, as shown.
